UNITED STATES PATENT OFFICE.

JOHN T. H. PAUL, OF CHICAGO, ILLINOIS, ASSIGNOR TO E. GOLDMAN & CO. INC., OF CHICAGO, ILLINOIS, A CORPORATION OF ILLINOIS.

FILTER.

13,053.

Specification of Reissued Letters Patent. Reissued Dec. 7, 1909.

Original No. 888,731, dated May 26, 1908, Serial No. 411,158. Application for reissue filed August 1, 1908. Serial No. 446,501.

To all whom it may concern:

Be it known that I, JOHN T. H. PAUL, a citizen of the United States, residing at Chicago, in the county of Cook and State 5 of Illinois, have invented a new and useful Improvement in Filters, of which the following is a specification.

My invention relates particularly to filters for use in filtering liquors, such as beer; and 10 my primary object is to provide a filter composed of a plurality of cells, each cell having few parts, and the filter being of high capacity, well adapted to perform with thoroughness the function of filtration, and 15 the filter-parts being capable of ready cleansing and, the construction being, therefore, sanitary in its nature.

The invention is illustrated in its preferred embodiment in the accompanying drawings, 20 in which—

Figure 1 represents a broken vertical sectional view of a filter constructed in accordance with my invention; Fig. 2, a broken plan view of a filter pan employed; 25 Fig. 3, a broken sectional view taken as indicated at line 3 of Fig. 2; Fig. 4, a broken sectional view taken as indicated at line 4 of Fig. 2; Fig. 5, a view partly in section and partly in elevation of a conduit-section 30 employed; Fig. 6, a broken perspective view of a packing-ring employed; Fig. 7, a sectional view of a pad or disk of filter material, which preferably is preparatorily formed before insertion in the filter; and Fig. 8, a broken sectional view illustrating a slight 35 modification.

In the construction illustrated, A represents a casing having a dished bottom A¹ and a removable top A²; B, an inner base- 40 plate supported on the casing bottom A¹; and B¹, a series of filter cells located in the casing and forming with the cylindrical wall of the casing an annular chamber B².

The casing A may be of any approved construction. In the construction shown, the casing bottom A¹ is equipped centrally with an outlet conduit a and at some distance therefrom with an inlet conduit a¹. The casing top A² is shown connected with an 45 external flange at the upper end of the cylindrical body of the casing by bolts a².

The inner base-plate B comprises a disk b equipped on its lower side with strengthening ribs b¹ and provided at its center with a

hollow hub or conduit-section b². The conduit-section b² has a reduced portion b³ at its lower end which fits within the hollow boss of the casing bottom A¹, and confined between the body of the conduit-section b² and the adjacent portion of the casing bottom A¹ is a gasket or packing b⁴. The conduit-section b² is provided at its upper end with an annular groove receiving a gasket or packing b⁵.

Each cell B¹ comprises a cell-pan, or support, b⁶, whose bottom is provided with a central perforation; a conduit-section b⁷ extending through said central perforation and provided externally with a flange b⁸ which rests upon the upper surface of the bottom of the pan; a packing ring b⁹ encircling the conduit-section and between which and the flange b⁸ the central portion of the pan-bottom is confined; a packing-ring b¹⁰ connected with the lower outer margin of the pan-bottom; a packing-ring b¹¹ resting upon the upper outer marginal surface of the pan-bottom; and a filter mass, or disk of filtering material b¹² which substantially fills the pan. The pan-bottom is provided at intervals with radial corrugations b¹³ joined by part circular corrugations b¹⁴, as clearly appears from Figs. 2, 3 and 4. The pan-bottom also has a flat marginal portion b¹⁵ adjacent to the vertical flange b¹⁶ which constitutes the circumferential wall of the pan. The flat marginal portion b¹⁵ of the bottom is substantially in the plane of the upper portions of the corrugations, or, in other words, is raised with relation to 75 the extreme bottom portion of the pan. The pan bottom has a central perforation b¹⁷ and a marginal flat portion b¹⁸ adjacent thereto. The flat inner marginal portion b¹⁸ is substantially on a level with the lower 80 portions of the corrugations of the pan-bottom, or, in other words, is depressed beneath the plane of the outer flat marginal portion b¹⁵ of the pan-bottom. The pan-bottom being corrugated, as described, has 85 grooves on its upper surface which serve in collecting the filtered liquor and conducting it to the central outlet conduit, and has channels or grooves on its lower surface which serve in distributing the unfiltered 90 liquor over the upper surface of the filtering material, or filter pad. As stated, the flange b⁸ of the conduit-section b⁷ bears upon 95 100 105

the upper surface of the inner marginal flat portion b^{18} of the pan-bottom, and extending through the conduit-section are radial openings b^{19} which register with the radial grooves which the corrugations b^{18} afford on the upper surface of the pan-bottom. The upper surface of the flange b^8 affords a shoulder b^{20} , the flange acting as a packing-ring co-acting with the packing-ring b^9 of the filter cell above. The lower end of the lowermost conduit-section b^7 fits within the upper end of the conduit-section b^2 , and the upper end of the lower-most conduit-section b^7 receives the lower end of the next 10 mounting conduit-section, and so on. The packing-rings b^{10} are provided at their upper portions with radial perforations b^{21} which register with the radial grooves on the lower side of the cell pan bottoms. The 15 packing-ring b^{10} on the lower side of the outer margin of each cell pan is of the right diameter to fit within the upper portion of the vertical flange of the cell pan beneath, as shown. The disks of filtering material 20 b^{12} are preferably preparatorily formed in a suitable press. When the filter parts are assembled, the pads or disks b^{12} are again placed under compression, the packing-rings at the outer and inner margins serving to prevent seepage of the liquor along 25 the vertical flanges of the cell pans, so that the liquor will be forced to filter through the filter pads. The corrugations in the bottoms of the cell pans are deep and relatively narrow, so that it is practicable to 30 allow the pads of filtering material to rest directly upon the corrugations, thereby dispensing with the fiber-retaining screens which are common in filter construction, 35 and, in the illustration given in Fig. 1, the lower side of the pad of one cell contacts directly with the corrugations in the bottom of the containing-pan, or support, and the upper side of said pad contacts directly 40 with the corrugations of the bottom of the 45 next surmounting pan.

If desired, a fiber-retaining screen b^{22} may be placed upon the corrugated bottom of the cell pan beneath the filter-pad b^{12} , as illustrated in Fig. 8. Where a pad of good quality and long fiber is employed, the fiber-retaining screen b^{22} is unnecessary, however.

The casing top A^2 is equipped centrally on its lower surface with a boss or bearing b^{23} adapted to bear upon the upper end of the uppermost conduit-section b^7 , and the boss b^{23} is surrounded by a packing-ring b^{24} which co-acts with the shoulder b^{20} of the 55 uppermost conduit-section. The casing top is also equipped near its periphery on its lower side with a packing-ring b^{25} which is received in the upper portion of the uppermost cell pan. The packing-ring b^{25} is provided with radial perforations b^{26} and the

lower side of the casing top is provided with grooves b^{27} , enabling the liquor to be distributed over the upper surface of the filter-pad in the uppermost cell.

The manner of assembling the parts of the filter will be readily understood. As stated, the pads or disks b^{12} are preferably preparatorily formed before insertion in the filter, but are subjected to pressure after insertion in the filter when the bolts a^2 are tightened. 75 In operation, the liquor enters through the conduit a^1 and passes to all parts of the annular chamber B^2 , from whence it passes through the admission ports b^{21} of the several cells, being distributed over the upper surface of the filter pads, whence it passes through the filter pads to the channels in the bottoms of the cell pans, from whence the liquor escapes through the openings b^{19} of the central conduit-sections. 80

The foregoing detailed description has been given for clearness of understanding only, and no undue limitation is to be understood therefrom.

What I regard as new, and desire to secure by Letters Patent, is—

1. In a filter, the combination of a plurality of cells, each cell comprising a cell pan, or support, having its bottom provided on both sides with grooves, and provided centrally with a perforation, a conduit-section extending through said perforation, a packing-ring at the lower outer marginal surface of each cell pan bottom, the packing-ring of one cell pan being received in the upper portion of the cell pan beneath, and each packing-ring being provided with perforations, ports opening through said conduit-sections and communicating with the grooves on the upper sides of the cell pan bottoms, and filter-masses in said cell pans. 100

2. In a filter, the combination of a plurality of cells, each cell comprising a cell pan having a corrugated bottom affording

grooves on both sides of the bottom, the bottom having a central perforation, a conduit-section extending through said perforation and equipped with an external flange serving as a packet-ring located above the upper marginal surface surrounding said perforation, said conduit-section having perforations communicating with the grooves on the upper surface of the cell pan bottom, a packing-ring surrounding the conduit-section beneath the cell pan bottom, a packing-ring at the lower outer marginal surface of the cell pan bottom provided with perforations communicating with the grooves on the under surface of the cell pan bottom, the last-named packing-ring of each cell pan bottom being received in the upper portion of the cell pan beneath, and a filter-mass confined between the bottom of each cell pan and the lower surface of the bottom of the next superposed cell pan. 115

120

125

130

3. In a filter, the combination of a plurality of cells, each cell comprising a cell pan having a corrugated bottom provided with a central perforation and having a raised flat outer marginal portion and a depressed flat inner marginal portion, a conduit-section having an external flange bearing upon the upper surface of the inner marginal portion of the cell pan bottom, said conduit-section having perforations communicating with the grooves on the upper surface of the cell pan bottom, the lower portion of the conduit-section being of a reduced diameter, a packing-ring on the conduit-section beneath the lower surface of the inner margin of the cell pan bottom, a packing-ring applied at the lower surface of the outer marginal portions of the cell pan bottom and provided with perforations, said last-named packing-ring of one cell pan bottom being received within the upper portion of the cell pan beneath, and a filter-mass in the cell pan confined between the cell pan bottom and the lower surface of the bottom of the next superposed cell pan.

4. In a filter, the combination of a plurality of filter-cells, each cell comprising a cell pan, or support, having a corrugated bottom and a central perforation, and having a raised flat outer marginal portion and a depressed flat inner marginal portion, a conduit-section extending through said central perforation and having an external flange bearing upon the upper surface of the inner marginal portion of the cell pan bottom, and perforations extending therethrough and communicating with the grooves on the upper surface of the cell pan bottom, a packing-ring encircling the conduit-section and bearing against the lower surface of the inner marginal portion of the cell pan bottom, a packing-ring bearing upon the upper surface of the outer marginal portion of the cell pan bottom, a packing-ring applied at the lower surface of the outer marginal portion of the cell pan bottom and provided with perforations communicating with the grooves on the lower side of the cell pan, and filter masses in said cell pan.

5. In a filter, the combination of a plurality of cells, each cell comprising a cell-pan, or support, having a bottom provided with deep and narrow corrugations and provided centrally with a perforation, a conduit-section extending through said central perforation, packing-rings above and beneath the cell pan bottom at said conduit-section, packing-rings above and beneath the cell pan bottom at the outer marginal portion thereof, and a disk of filtering material in or on each cell-pan, or support, and resting directly upon the corrugated bottom thereof.

6. In a filter, the combination of a casing having a central outlet conduit, an inlet conduit, and a plurality of cells within said

casing and forming with the cylindrical wall of the casing an annular chamber, each cell comprising a cell pan having a corrugated bottom and a central perforation, a conduit-section extending through said central perforation and having an external flange forming a packing-ring at one side of the cell pan bottom, a packing-ring applied to the conduit-section at the opposite side of said cell pan bottom, said conduit-section having perforations and communicating with the grooves on the under surface of the cell pan bottom, a packing ring applied to the upper surface of the outer marginal portion of the cell pan bottom, a packing-ring applied to the lower surface of the outer marginal portion of the cell pan bottom, said last-named packing-ring having perforations communicating with the grooves on the lower side of the cell pan bottom, the last-named packing-ring of one cell pan bottom being received within the upper portion of the cell pan beneath, and a single pad of filtering material confined in each cell pan.

7. In a filter-cell, the combination of a cell pan, or support, having a corrugated bottom and provided with a central perforation, the bottom of said cell pan having an elevated flat marginal portion adjacent to the vertical flange of the cell pan and having a depressed flat marginal portion surrounding the central perforation, a packing-ring applied to the lower surface of the cell pan bottom at the outer flat marginal portion thereof and provided with radial openings, an externally flanged conduit-section extending through said central perforation, the flange bearing upon the upper surface of the inner flat marginal portion of the cell pan bottom, the conduit-section having radial perforations communicating with the grooves on the upper surface of the cell pan bottom, and a packing-ring applied to the conduit-section at the lower surface of the inner flat marginal portion of the cell pan bottom.

8. In a filter-cell, a cell pan having a corrugated bottom and a central perforation, a packing-ring applied to the lower surface of the outer marginal portion of the cell pan bottom and having openings therethrough communicating with the grooves on the lower surface of the cell-pan bottom, and a conduit-section extending through said central perforation and provided with perforations communicating with grooves on the upper surface of the cell-pan bottom.

9. In a filter cell, a cell-pan, or support, having a bottom provided with corrugations and with a central perforation and provided with a flat raised outer marginal portion and a flat depressed inner marginal portion, a packing-ring applied to the lower surface of said outer flat marginal portion

of the cell pan bottom and provided with openings extending therethrough, a conduit-section extending through said central perforation and having an external flange bearing upon the upper surface of the inner marginal portion of the cell pan bottom, said conduit-section having perforations therethrough communicating with the grooves on the upper surface of the cell pan bottom, and a packing-ring encircling said conduit-section and bearing against the lower surface of the inner marginal portion of the cell pan bottom.

10. In a filter, the combination of a casting, a plurality of superposed filter cells therein and forming therewith an annular

chamber, each cell comprising a pan provided with a bottom which is corrugated to afford closely related grooves on both sides throughout substantially its whole area, said pan having an upturned flange at its periphery, a central conduit extending through the pan-bottoms and communicating with the grooves on one side thereof, the grooves on the other side of said bottoms communicating with said annular chamber, and filter masses confined between said bottoms and contacting directly therewith.

25 JOHN T. H. PAUL.
